FIG. 2.

INVENTOR

Jack Schumer

UNITED STATES PATENT OFFICE

110,836

DESIGN FOR A COAT

Jack Schumer, New York, N. Y.

Application June 29, 1938, Serial No. 78,129

Term of patent 3½ years

To all whom it may concern:

Be it known that I, Jack Schumer, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein,

The characteristic features of my design reside in the specific sleeves and leather trimmed collar, in combination with the specific coat, as shown.

I claim:

The ornamental design for a coat, substantially as shown and described.

JACK SCHÜMER.
